UNITED STATES PATENT OFFICE.

ELA CHLOE LAIRY, OF LOGANSPORT, INDIANA.

HAND PROTECTOR.

Application filed April 11, 1927. Serial No. 182,895.

This invention relates to improvements in the type of hand protector ordinarily employed in handling culinary and other implements where it is necessary to protect the hands from exposure to burns.

It is the object of the invention to provide a protector which is capable of being partially folded and secured in such folded condition as to present a pocket or stall which, upon the insertion of the thumb of the hand maintains the protector against accidental displacement in the position in which it most effectively shields the hand against contact with any part of the heated implement.

A further object is the provision of means permitting of detachment of the fold whereby the device may be extended into such flat form as to facilitate the use thereof in handling other implements than those equipped with handles and for sanitary reasons for instance in the resulting possibility of washing the protector.

A still further object is the provision of a protector of such shape and structure as to render it highly economical from the standpoint of both consumption of material necessary in production and in the actual manufacture thereof.

In the accompanying drawings wherein an improved embodiment of the invention is illustrated:

Figure 1 is a perspective view of the protector showing it applied to a hand.

Figure 2 is a plan view thereof in extended or flat condition also showing, in dotted lines, the manner of folding and securing the same.

Figure 3 is a perspective view showing the protector suspended from a supporting hook.

Figure 4 is a detail sectional view showing fastening means arranged on both sides of the protector.

Referring to the drawing in detail, 5 indicates the protector which is substantially rectangular in form and constructed of any appropriate material as for instance fabric possessing a requisite degree of durability and heat resistance. The shape of the body is such as to provide two relatively short sides 6 and two longer sides 7, such shape being of some importance as the following description will reveal. At a point adjacent one short edge 6, but a greater distance from the other short edge is secured one part 8 of a snap fastener.

The companion fastener part 9 is secured

to the body at a point further removed from the first mentioned short edge 6, and approximately the same distance from the adjacent long edge 7. The location of the two parts of the fastener is such that when the corner defined by the meeting point of the two short edges 6 is folded back along the oblique line indicated by the dotted lines at 10 in Figure 2, said fasteners will be in engaging positions.

The advantage in the provision of the long edges 7 is that when the sheet is folded upon itself at one corner and secured by the snap fastener 8-9, and the thumb is inserted in the pocket or stall thus formed the length of the portion of the protector which overlies the palm and fingers of the hand is such as to practically cover them and afford ample protection. It is evident that it is desirable to space the parts 8 and 9 of the fastener such a distance apart that a close fit of the thumb in the pocket formed by folding is assured and accordingly the protector by the simple and convenient act of inserting the thumb in the folded portion is securely held against such accidental displacement as might cause the unintentional release of the utensil or injury to the hand.

As a matter of convenience in supporting the protector when not in use, a supporting ring 11 is attached to the body at a point opposite the fastener part 8 which, as suggested in Figure 3 may be employed for suspending the body from a hook 12.

When occasion requires the protector may be used in the form of a flat sheet of protective material for handling a utensil or for any other purpose by disengaging the snap fastener 8-9 and unfolding the turned over portion which forms the thumb stall and, if desired, refolding into any other shape or dimension required. A further advantage in having the protector in the form of a flat sheet of material with small fastening means to provide a thumb-stall for holding it on the hand is that it may be readily and easily washed and dried to insure the continued sanitary condition thereof.

For the convenience of left-handed persons, it is desirable that a second set of snap fasteners 8^a and 9^a be secured to the reverse side of the body 5 so that the flap portion 6 may be folded in either direction over the part 5 to adapt the protector to either the left or the right hand.

It will be noted that in either arrangement

of the hand protector, to fit the right or left hand, the location of the cooperating fastening means with respect to each other provides an open-ended thumb-stall through 5 which the thumb projects, and said connected fastening means form a stop against which the base of the thumb will abut to properly position the protector on the hand.

What I claim is:

- 10 1. A hand protector or covering comprising a sheet of material substantially rectangular in shape, and spaced apart fastening means attached to one side of said sheet for retaining a folded portion thereof in connection with the body portion to provide a thumb-stall for holding the protector on the hand.
- 20 2. A hand protector or covering comprising a sheet of material substantially rectangular in shape, and detachable fastening means attached to one side of the sheet with one member of said fastening means located near one corner of the sheet and the other member located on the body of the sheet a 25 suitable distance from said companion member and nearer the transverse center of the sheet to provide a thumb-stall and stop by folding the aforesaid corner portion of the

sheet upon the body portion and engaging the fastening members one with the other.

3. A hand protector or covering comprising a sheet of material substantially rectangular in shape, and a snap fastener both members or parts of which are attached to one side of the sheet with one part located near one corner of said sheet and the other on the body portion thereof a suitable distance from said companion part and nearer the transverse center of the sheet to provide a thumb-stall and stop for limiting the insertion of the thumb in the stall by folding the corner portion of the sheet upon the body portion thereof and engaging the parts of the fastener.

4. A hand protector or covering comprising a sheet of material substantially rectangular in shape, and companion snap fasteners attached to both sides of said sheet, the parts of the snap fastener on each side being spaced apart and located with respect to a corner of the sheet to provide a thumb-stall when said corner portion of the sheet is folded upon the body portion at either side thereof.

In testimony whereof I affix my signature.
